UNITED STATES PATENT OFFICE.

CLAUDE B. BAILEY, OF WYANDOTTE, MICHIGAN, ASSIGNOR TO MCCORD MANUFACTURING COMPANY, OF DETROIT, MICHIGAN, A CORPORATION OF NEW YORK.

GASKET.

Application filed October 13, 1921. Serial No. 507,475.

To all whom it may concern:

Be it known that I, CLAUDE B. BAILEY, a citizen of the United States, residing at Wyandotte, in the county of Wayne and State of Michigan, have invented new and useful Improvements in Gaskets, of which the following is a specification.

This invention relates to gaskets of the combined metal and asbestos type.

10 One object of my invention is to provide the sheet metal body of the gasket with but one guide flange so as to have a gasket of that kind for use in places where needed or necessary. Another object is to reinforce or strengthen said guide flange against inward bending when the flange strikes against the edge of a hole or port of the part into which it is inserted in the application of the gasket in its position of use.

20 In the accompanying drawings—

Fig. 1 is a bottom view, partially in section of a gasket constructed in accordance with my invention;

25 Fig. 2 is a diametrical sectional view taken on line 2—2 of Fig. 1;

Fig. 3 is an enlarged transverse sectional view through one side of the gasket to more clearly illustrate the structure; and

30 Fig. 4 illustrates two of my improved gaskets in positions of use.

A gasket constructed in accordance with my invention is annular and has a body portion made of sheet metal, such as copper. This is bent or formed to provide a single 35 tubular guide flange 1 on one side only of a flange 2 at the base of said guide flange and arranged substantially at right-angles thereto. Said flange 2 extends outward from the guide flange 1 and bears against the inner face of a ring 3 of fibrous material, such as asbestos. The outer marginal portion 4 of said base flange 2 extends about and covers the outer annular edge of the ring 3 and overlaps the outer face thereof, 45 as shown in Figs. 1 to 3.

Inside of the guide flange 1 is a reinforcing or strengthening flange 5. The flange 5 is integral with the guide 1 at the outer edge thereof by bending the portion forming said flange 5 inward on the flange 1 and thus providing a folded edge of metal around the upper edge of said flanges. The flange 5 extends to the ring 3 and over the inner annular edge thereof to cover and protect the 55 same. The inner or free marginal portion

6 of said flange 5 is bent to overlap the outer face of the ring 3 and extend toward the flange 4, as shown in the drawings. These flanges 4 and 6 terminate short of each other and expose the portion of the ring 3 there-between for seating purposes.

By the construction described, the fibrous ring 3 is held in place by the flanges which make the metallic body portion of the gasket, and the latter is provided on one side only with a tubular guide flange 1, which in turn is reinforced against bending by the strengthening flange 5.

In Fig. 4, I have shown an intake manifold 7 and an exhaust manifold 8. These register with ports 9 and 10, respectively, in the wall 11 of the engine casing when the manifolds are in use and clamped against said wall, as shown. For each manifold there is a gasket of my invention for the 75 joint between the manifold and the wall 11. When applying the manifold against the wall, a gasket is either first applied to the manifold before the latter is applied to the engine, or to the engine before the manifold is applied thereto. In either case, the tubular flange 1 is inserted into the open end of the manifold or the cylinder port, as the case may be, until stopped by contact with the flange 2. This connects the gasket 80 with the manifold or the engine, as the case may be. For illustrative purposes, I have shown the positions of the gaskets reversed in Fig. 4. One gasket has its guide flange 1 in the manifold, and the other has its guide 85 flange in the cylinder port.

The gasket is not limited to the use mentioned, but may be used in places where but a single guide flange is needed or desired. As shown in Fig. 3, the guide flange 1 is 90 slightly tapered to accommodate itself to the hole or port into which it is inserted. Moreover, said flange 1 is bulged slightly outward to more readily grip in the opening and thus hold the gasket from accidentally 95 falling out.

While I have shown and described herein in detail a gasket constructed in accordance with my invention, it is to be of course understood that the details of construction and arrangement of parts may be variously changed and modified without departing from the spirit and scope of my invention.

I claim as my invention:

1. A gasket, comprising a packing ring,

- and a metallic portion formed to provide an annular section engaging said ring about the inner and outer edges thereof, and a tubular guide member on one side only of said section and extending outward from the inner edge of the same, the opposite side of said section being free of projections and constituting the seat for said section on the side opposite said guide member.
- 10 2. A gasket, comprising a packing ring, and a metallic portion formed to provide an annular section engaging said ring about the inner and outer edges thereof, and a tubular guide member on one side only of said section and extending outward from the inner edge of the same, the opposite side of said section being free of projections and constituting the seat for said section on the side opposite said guide member, said seat being open between the inner and outer edges thereof to expose the ring through the same.
- 15 3. A gasket, comprising a packing ring, a metallic portion formed to provide an annular section engaging said ring about the inner and outer edges thereof, and a tubular guide member on one side only of said section and extending outward from the inner edge of the same, the opposite side of said section being free of projections and constituting the seat for said section on the side opposite said guide member, and means for strengthening said guide member against bending.
- 20 4. A gasket, comprising a packing ring, and a metallic portion formed to provide an annular section engaging said ring about the inner and outer edges thereof, and a tubular guide member on one side only of said section and extending outward from the inner edge of the same, the opposite side of said section being free of projections and constituting the seat for said section on the side opposite said guide member, said guide member being formed of connected inner and outer flanges to strengthen the same against bending.
- 25 5. A gasket, comprising a packing ring, and a metallic portion formed to provide an annular section engaging said ring about the inner and outer edges thereof, and a tubular guide member on one side only of said section and extending outward from the inner edge of the same, the opposite side of said section being free of projections and constituting the seat for said section on the side opposite said guide member, said guide member being folded on itself to provide a double thickness of metal to strengthen the same against bending.
- 30 6. A gasket, comprising a packing ring, and a metallic portion formed to provide an annular section engaging said ring about the inner and outer edges thereof, and a tubular guide member on one side only of said section and extending outward from the inner edge of the same, said guide member being folded on itself to provide a double thickness of metal to strengthen the same against bending, said ring being exposed through said section on the side opposite to said guide member.
- 35 7. A gasket, comprising a packing ring, and a sheet metal portion bent to provide a tubular guide member on one side only of said ring and extending outward from the inner edge thereof, said guide member being folded on itself to provide inner and outer flanges, an annular flange at the base of and integral with said outer flange and bearing against the side of said ring from which said guide member extends, said base flange having its outer marginal portion bent about the outer edge of said ring and inward over the side opposite said base flange, said inner flange extending over the inner edge of said ring and having its marginal portion bent over the side of said ring opposite said base flange and terminating short of the inwardly bent margin of said flange to expose the ring between the same.
- 40 8. A gasket, comprising a packing ring, and a metallic portion formed to provide an annular section engaging said ring about the inner and outer edges thereof, and a tubular guide member on one side only of said section and extending outward from the inner edge of the same, the opposite side of said ring being free of projections and constituting the seat for said section on the side opposite said guide member, said guide member being folded on itself to provide a folded outer edge therefor and inner and outer flanges, the outer flange being slightly tapered and provided with an outwardly bulged portion.
- 45 9. In testimony that I claim the foregoing as my invention, I affix my signature this 10 day of October, A. D. 1921.
- CLAUDE B. BAILEY.
